COMBINED RADIO INTERFERENCE SHIELD AND WIRE SUPPORT FOR ENGINE DISTRIBUTORS

Russell G. Livingston, Los Angeles, Calif., assignor to Hallett Manufacturing Company, Los Angeles, Calif., a corporation of California

Filed May 23, 1963, Ser. No. 75,015

Term of patent 14 years

(Cl. D77—1)

FIG. 1.

FIG. 2.

FIG. 3.

FIG. 4.

FIG. 1 is a top plan view of a combined radio interference shield and wire support for engine distributors showing my new design;

FIG. 2 is a side elevation thereof;

FIG. 3 is a side elevation thereof looking toward the right side of FIG. 1; and

FIG. 4 is a sectional view thereof taken on the line 4-4 of FIG. 2.

I claim:

The ornamental design for a combined radio interference shield and wire support for engine distributors, as shown.
